DENTAL AND SURGICAL ABRASIVE JET APPARATUS

Renato E. Cassani, Alameda, Calif.

Application May 11, 1953, Serial No. 354,185

15 Claims. (Cl. 32—58)

This invention relates to apparatus for providing a jet of finely divided abrasive solids suspended in a propelling gas suitable for impingement upon a restricted area of hard ectodermal and mesodermal tissue, for cutting, boring, cleaning or polishing the same. In dentistry and in such surgical operations as trephining, the jet contains abrasives of sufficient hardness to cut away a tooth or a bone, while in oral hygiene the jet contains softer abrasives. Such jets are used as an adjunct to or, in some instances, as replacement for rotary drills, burrs, and related power-driven equipment. For example, in dentistry such a jet is used to cut away tooth enamel in preparing a cavity; in most cases the cavity is further shaped and softer dental caries is removed by conventional rotary or other implements.

Apparatus for forming a jet of finely divided abrasive solids are already known, but are complex and expensive due to the need to entrain the solids in the propelling gas at a regular rate, this regular entrainment being particularly difficult in the case of jets for dental and surgical apparatus because of the small quantities involved for producing narrow jets usually less than one millimeter in diameter. Abrasive cutting jets in dentistry and surgery in particular must be directed against a confined target area and must maintain a uniform cutting action over sufficient periods of time to complete a desired cut except insofar as the cutting action is deliberately varied by the operator. The intensity of the cutting action depends, apart from the hardness and shape of the solid abrasive material, upon the kinetic energy of the individual solid particles, that is, upon their velocity when the particle sizes are substantially uniform, and upon the number of particles striking the tooth in unit time; for a jet wherein the particles move with a uniform speed the particles impinge on the target area at a rate that is proportional to the solids content of the jet per unit of volume of propellant gas at the conditions of the jet. This solids content is for brevity herein referred to as the jet density.

With a regulated supply of propellant gas the velocity of the gas and, hence, of the entrained solids in the jet can usually be held more or less constant unless the solids entrainment unit is of a type that offers a variable or surging resistance to the passage of the gas or the solids are fed into the gas at a fluctuating rate. The entrainment of the solids by the gas in small amounts at a regular rate has, however, been difficult, and mechanical solids feed devices have been unreliable and/or expensive. When a stream of gas is passed through or in proximity to a source body of finely divided solids to effect direct entrainment with a view to eliminating the mechanical feed device, two difficulties manifest themselves: surging and dwindling. By surging is meant the periodic change in the density of the jet; this is believed to be due to uncontrolled periodic movement of the source body of solids which causes a periodic change in the surface of such body exposed to the current of entraining gas. By dwindling is meant a progressive, usually gradual decrease in the density of the jet as the supply of solids becomes depleted, continu-

ing until the reservoir of solids is replenished or, in some cases, shaken to cause a rearrangement of the solids. These difficulties have heretofore made it necessary to use special devices for insuring the regular entrainment of the solids in the propelling gas stream.

Control of the cutting or polishing operation can be effectively attained only by a jet in which the density and the velocity of the solids remain constant unless deliberately altered by the operator. Variations in the density of the jet affect the cutting speed also in that too high a density under some conditions causes solids to accumulate in the cut, e. g., in the tooth cavity, forming an obstruction to succeeding solids whereby the latter are prevented from striking the intended part of the hard tissue directly.

It is an object of this invention to provide a simple dental and surgical apparatus for forming a controlled jet of finely divided abrasive solids suspended in a propellant gas wherein the jet density and the particle velocity can be kept substantially free from random variations as considered above. Ancillary thereto, it is an object to provide an apparatus wherein the rate at which solids are entrained and the cutting rate can be readily altered by variation in the rate of flow of the gas, without the interposition of mechanical or electrical devices that act on the solids admitted to the gas stream.

A further object is to provide a pneumatic solids entrainment device suitable for use in dental and surgical apparatus of the type described wherein solids are stored in a canister that forms a reservoir and the solids are entrained in a propellant gas at a rate that is determined substantially solely by the rate of gas flow to form a suspension suitable for discharge from a nozzle.

Further objects will be apparent from the following description.

In summary, the apparatus according to the invention includes, preferably in the sequence recited, a source of gas under pressure, an entrainment device including a canister forming a reservoir for the finely divided abrasive solids and an entrainment chamber communicating with the canister, flow control means for the gas, and a discharge nozzle adapted for use in the mouth or on other parts of the body for directing the suspension formed in the entrainment device as a confined jet toward a restricted area of a tooth, bone, or the like. The improved entrainment device includes the said canister, an entrainment chamber formed by a tube or the like and situated preferably within the canister, said chamber being in communication with a lower part of the canister through one or more solids intake ports and having a gas inlet that provides a restricted passageway for directing the gas at a high velocity through the chamber past the intake ports and generate a low pressure region within the chamber near the ports, the chamber having an outlet to a conduit adapted to transport the suspension of solids formed in the chamber, and the canister being further in communication with the source of gas through a passageway arranged to agitate the supply of solids within the canister, said communication being preferably through the said entrainment chamber.

Having thus described the invention in a general way, the following detailed description of certain specific embodiments is made with reference to the accompanying drawings forming a part of this specification, wherein:

Figure 1 is a diagrammatic view of the apparatus;

Figure 2 is a vertical sectional view through the entrainment device;

Figure 3 is a horizontal sectional view taken on the line 3—3 of Figure 2;

Figure 4 is a horizontal sectional view taken on the line 4—4 of Figure 2;

Figure 5 is a vertical sectional view through an en-

trainment device according to a modified construction;

Figure 6 is an enlarged horizontal sectional view taken on the line 6—6 of Figure 5;

Figure 7 is a vertical sectional view through another modified embodiment of the entrainment device; and

Figure 8 is a horizontal sectional view taken on the line 8—8 of Figure 7.

Referring to Figure 1, the apparatus comprises a source of propelling gas, preferably dry, e. g., air or carbon dioxide under pressure, represented by a pressure cylinder 10, optionally provided with a pressure regulator 11 for maintaining a constant discharge pressure. It will be understood that other suitable sources of gas may be employed, such as a compressor which is commonly available as an accessory to a dental unit, which may be supplemented by a drying unit. The propelling gas passes through a supply pipe 12 to an entraining unit 13, wherein it becomes laden with abrasive solids. The resulting suspension is discharged through an outlet conduit 14 that advantageously has a sufficient small bore to insure a sustained high velocity to maintain the solids dispersed in the gas, whereby it is adapted to transport the suspension of solids without sedimentation. The conduit 14 is connected to a flexible hose 15 which is provided with a flow control device 16 of any suitable type, e. g., a pinch device, and is connected to a discharge nozzle 17 which is preferably provided with a rigid hand part and a discharge part 17a of small external size suitable for manipulation, e. g., within the mouth of a patient. Such a nozzle, being known per se, will not be described in detail. It may be said, however, that such a nozzle may, for example, have a bore with a diameter of about 0.5 mm. (millimeters), although bores of other diameters may be used in certain cases, e. g., for oral hygiene, where somewhat larger bores are suitable, or for making exceptionally fine cuts, when smaller bores can be used. The bore in the discharge part 17a should preferably be streamlined to emit a jet that maintains its diameter for distances several times the diameter thereof, e. g., from 1 to 3 mm., without appreciable divergence. The flow controller 16 may be operated to permit gradations in the flow rate by a treadle, for convenient operation by the dentist or surgeon and connected by any suitable mechanical, electrical or pneumatic connection, indicated diagrammatically by the dashed line 19. It will be understood that the pressure regulator valve 11 may, if desired, be omitted or combined with the flow controller, and that the latter may be placed ahead of the entraining unit or operated manually from the nozzle. It was found, however, that rapid control of the jet can be achieved by placing the flow controller as near to the nozzle as practicable.

The nozzle is used in a known manner to direct the abrasive jet against the tooth or other hard tissue while a suction device, not shown but known in the art, is placed into or near the mouth of the patient or other target area to remove spent solids.

The entrainment unit 13 may be constructed as shown in Figures 2—4, wherein 20 represents a canister of circular cross-section and of sufficient strength to withstand the pressure of the gas. The canister has a threaded neck by which it is secured to a knurled coupler 21 that is threaded to an elbow pipe 22. The latter is connected to and supported from the pipe 12 through a swivel joint that includes an externally threaded, flanged tube 23 and a knurled ring 24 having a flange 24a that may be spun over the flange 22a of the elbow. By loosening the ring 24 the elbow 22 can be rotated to bring the coupler 21 to a position beneath the pipe 12, permitting a canister containing finely divided abrasives to be attached. Thereafter the canister and elbow can be rotated to the operative raised position shown and clamped by the ring 24.

The canister contains a central tube 25 defining within itself an entrainment chamber and secured within a bushing 26 that is threaded within the coupler 21. The tube

may be secured by means of an annulus 27 that is brazed or pressed fixedly to the tube and is held against the bushing by a coupling ring 28 that is threaded to the bushing. The bottom of the tube is closed by a circular floor plate 29 and the top is closed by a cap 30 that has a central positioning boss 30a. Near the bottom of the tube are a plurality, e. g., four solids intake ports 31. Gas is admitted into the bottom of the chamber above the floor plate through a constriction to insure a high upward velocity past the ports 31. According to the preferred embodiment shown, a separate gas stream is provided for each port, and this may be attained by mounting a corresponding number of fine capillary tubes 32, e. g., having diameters from 0.2 to 2 mm., depending upon their number and the total gas flow, in holes in the plate 29. For example, four capillary tubes with 0.5 mm. bores are suitable when the tube 25 is 1 cm. in internal diameter. For high velocity jets, approaching the critical sonic velocity, it is desirable to use convergent-divergent bores, as shown in Figure 5.

The canister is placed in communication with the source of gas through a passageway including a flow director for agitating the solids therein. In this embodiment the passageway includes a plurality of helical tubes 33 and 34 that are mounted on the tube 25 in communication with the upper end thereof and extend downwardly so as to discharge gas downwardly and slightly outwardly, toward the periphery of the canister bottom with a whirling motion, the helical tubes in this constituting the said flow director.

The outlet conduit 14 extends concentrically within the tube 25 from the boss 30a which fits into the top to close and position the upper end. The conduit extends through the floor plate 29 and the outer wall of the elbow 22, to which it is sealed by an O-ring 35 and gland 36. The conduit 14 is in flow communication with the entrainment chamber through a plurality of side discharge ports 37 situated above the solids intake ports 31 by a distance sufficient to cause the gas velocity to become substantially uniform over the cross-section of the entrainment chamber, whereby pressure recovery occurs and the pressure at the ports 37 is higher than that at the ports 31. The ports 37 are advantageously below the top of the tube 25 as shown when the latter is longer than the length required to satisfy the above-noted pressure effect, so that the gas withdrawn from the entrainment chamber through the conduit 14 will contain a greater or a more uniform quantity of solids, particularly at low gas flow rates when a certain amount of settling of the solids in the tube 25 may occur.

The operation of the entrainment device is as follows: Finely divided abrasive, e. g., aluminum oxide or dolomite with particle diameters of about 10 to 50 microns is placed in the canister. These and other materials are suitable for cutting, but dolomite, being softer, is preferred for dental prophylaxis. The particles are advantageously graded so as to avoid a wide range of particle sizes. Gas under pressure, e. g., from 30 to 100 lbs. per sq. in. gauge or higher is supplied from the pipe 12 and flows upwards at high velocity through the capillary tubes 32 and thence at reduced velocity through the tube 25. A part of the gas flows through the helical tubes 33 and 34 into the canister, impinging on the source body of solids therein to agitate them and form a dense cloud. Due to this agitation the solids are conditioned to be drawn into the entrainment chamber through the solids intake ports 31, together with gas from the canister. The passage of the solids through these ports is induced by the high velocity jets emitted from the capillary tubes 32, which causes a low pressure region within the tube 25 opposite each intake port. The gas moves at lower velocity in the upper part of the tube 25 and at still lower velocity in the canister, so that a progressive recovery of pressure occurs and the pressure in the canister outside of the entrainment chamber exceeds

that within the chamber. In this manner a continuing flow of solids and gas into the tube 25 is induced, resulting in the upward entrainment of solids in the gas to form a suspension. A part of this suspension is discharged through the discharge ports 37 into the outlet conduit 14 to form the jet emitted from the nozzle 17. It is evident that the gas discharged through the helical tubes will also contain suspended solids, so that a circulation of solids occurs, and that the gas flow in the conduit 14 equals that admitted from the pipe 12.

The agitation of the solids within the canister constitutes an important feature of the invention. It is only by this expedient that the regular flow of solids into the entrainment chamber is effected, without surges and without significant diminution in the density of the suspension as the supply of solids in the canister becomes depleted. Moreover, the response of the system to changes in the gas flow is rapid. When the pedal 18 is released to stop the flow of gas circulation stops almost immediately, and only a second or less is required to start the circulation of solids after the pedal is depressed to start the flow of gas. The circulation of solids becomes less at reduced gas velocity, resulting in the discharge of solids from the device through the conduit 14 at a lower rate when the pedal 18 is partially released. This reduces the cutting power of the jet. It thereby becomes unnecessary to provide a mechanical or electrical device for determining the rate at which solids are admitted to the gas stream.

This disposition of the discharge ports 37 in the side of the conduit 14 was found to give excellent results. While discharge of the suspension through the upper end of an open discharge conduit can be used, this requires the solids to make a change of direction through 180° before entering the conduit and results in the discharge of a gas stream containing a lower density of solids than in the embodiment shown, wherein only a 90° change of direction occurs prior to entering the ports. However, the invention is not restricted to the arrangement shown.

To prevent adventitious solids particles from clogging the capillaries it is desirable to use a gas that is free from moisture, and a drying unit is advantageously employed when the gas is atmospheric air that is pressurized. The use of dry gas is further desirable for preventing agglomeration of the solids within the canister; such agglomeration may cause interference with the regular circulation of the solids in the manner described above and may clog the nozzle 17.

Referring to Figures 5 and 6, the modified entraining device illustrates several variants that can be applied individually or in combination to the embodiment previously described. This device includes a canister 40 which may be circular or rectangular in cross-section and has a removable top closure 41 with a threaded filling opening, that is normally closed by an inverted cap 42. The bottom 43 is thickened at the center and has a central, internally threaded hole into which the tube 44, forming the entrainment chamber is screwed. The tube is closed at the bottom by a permanently fixed orifice plate 45 having small convergent-divergent orifices 46 extending therethrough, corresponding in number to and situated adjoining solids intake ports 47 in the tube just above the orifice plate. For example, four such ports and orifices may be provided, the latter having the sizes previously described. The top of the tube has threaded connection with a head 48 having a pair of discharge tubes 49 and 50 the outlets of which are directed downwardly and slightly outwardly, approximately toward the bottom of the canister side wall. A gas box 51 is mounted beneath the bottom 43 by screws 52 and has a partition 53 dividing it into an upper and lower gas supply chamber. The former is supplied with gas under pressure through a supply pipe 54 and the latter commu-

nicates to an outlet conduit 55 that is adapted to transport the suspension.

A rotatable outlet tube 56 extends vertically through the box 51 and plate 45 and concentrically into the tube 44 and has the upper end thereof positioned by a deflector cap 57 that may be integral with a sleeve 58 fixed within the tube 44 by a screw 59. The deflector-sleeve structure provides large openings 60 for the upward flow of gas, and the tube 56 is rotatable with respect to the deflector 57. As shown in Figure 6, the deflector has two wings, and preferably has rounded edges so as to have parts of each wing extend to progressively different distances beyond the tube 56. The outlet tube has a collar 61 bearing against the partition 53 to prevent downward movement of the tube, a pair of diametrically opposed side suspension intake ports 62 immediately beneath the deflector, and a plurality of vertically elongated discharge ports 63 within the discharge chamber. It is sealed to the bottom of the box 51 by an O-ring 64 and a gland 65. An operating lever or handle 66 is attached to the bottom of the tube 56.

The operation of the device according to Figures 5 and 6 is similar to that previously described in that the propelling gas supplied from the pipe 54 flows upwards through the orifices 46 at high velocity past the solids intake ports 47 to draw solids and gas from the canister into the tube 44 and form therein a suspension. A part of the gas, together with entrained solids, flows through the tubes 49 and 50 to agitate the solids in the canister; however, in this instance these tubes are situated in vertical planes and no swirling occurs. The remaining part of the suspension enters the ports 62, moves downward through the tube 56, and emerges through the ports 63 and the conduit 55.

According to a feature of this embodiment the density of the suspension withdrawn from the device can be varied. It will be noted that the gas flowing from the tube 44 into the ports 62 makes a change in direction. Part of the suspended solids, will separate from the gas due to inertia, unless otherwise guided, resulting in a discharged suspension that has a density somewhat lower than that ascending the tube 44. The deflector 57 assists in deflecting the solids to enter the ports 62. The effect of the deflector can, however, be varied by rotation of the tube 56 by means of the handle 66, bring the ports into alignment with the deflector wings or in positions displaced 90° therefrom entirely out of alignment with the deflector wings, or into intermediate positions. With the ports displaced from the deflector wings the deflector is almost ineffective to deflect solids and the discharged suspension has the lowest density; rotation to the position shown in the drawing, with the ports in alignment with the longest dimension of the deflector, the density is progressively increased.

Referring to Figures 7 and 8, showing a further modification, the entraining device includes a canister 70 having a removable top closure 71 and a vertical partition wall 72 separating the reservoir 73 for solids from the entrainment chamber 74. The partition has a plurality, e.g., four, solids intake ports 75 at the bottom. The bottom of the canister beneath the entrainment chamber 74 has an opening into which is inserted an orifice plate 76 which contains a plurality of orifices 77 positioned respectively near the several ports 75. A gas box 78 is secured beneath the orifice plate and is supplied with propelling gas under pressure by a supply pipe 79. The wall 72 is breached above the ports 75 to accommodate a flow director having an intake deflector 80 and a downwardly inclined spout 81. The top of the entrainment chamber is closed by the curved, top part of the wall 72 and communicates with an outlet conduit 82 adapted to transport a suspension.

In operation, finely divided solids having been placed in the reservoir part 73, propelling gas from the pipe 79 ascends at high velocity through the orifices 77 to create

a low pressure region opposite each solids intake port 75 and causing solids and gas to be drawn in. This forms an ascending suspension within the entrainment chamber 74. A part of this suspension is directed out from the entrainment chamber by the deflector 80 and downwards against the solids by the spout 81 to agitate the solids. The remaining part of the suspension is discharged through the conduit 82. The principles considered above apply to this embodiment, with the change that the suspension is discharged from the entraining device above the passage through which agitating gas is admitted into the canister.

It is evident that other changes may be made in the configuration and arrangement of parts without departing from the invention as defined in the appended claims. Thus, the flow director for directing the agitating gas into the canister may take other forms, including baffles or swirler vanes.

I claim as my invention:

1. An entrainment device for forming a suspension of finely divided abrasive solids in a small stream of propelling gas for use in dental and surgical abrasive jet apparatus which comprises, in combination, a canister forming a reservoir for said solids, a wall structure defining an entrainment chamber communicating with the canister through a solids intake opening, a gas inlet to said chamber adapted for connection to a source of said propelling gas under pressure situated near said solids intake opening and providing a restricted flow passage small in relation to the cross-section of the entrainment chamber for directing the gas at high velocity in proximity to said openings to generate a low pressure within the chamber at said opening and to form a suspension of said solids in the gas within the chamber, an outlet for discharging said suspension from the chamber, and means for admitting agitating gas into said canister, said means including a flow director for directing said agitating gas into the solids within the canister and said solids.

2. An entrainment device for forming a suspension of finely divided abrasive solids in a small stream of propelling gas for use in dental and surgical abrasive jet apparatus which comprises, in combination, a canister forming a reservoir for said solids, a wall structure defining an entrainment chamber communicating with the canister through a solids intake opening, a gas inlet to said chamber adapted for connection to a source of said propelling gas under pressure situated near said solids intake opening and providing a restricted flow passage small in relation to the cross-section of the entrainment chamber for directing the gas at high velocity in proximity to said opening to generate a low pressure within the chamber at said opening and to form a suspension of said solids in the gas within the chamber, an outlet for discharging said suspension from the chamber, a passageway connected to said entrainment chamber to receive a portion of said suspension therefrom, and a flow director for directing the said portion of the suspension into the solids within the canister to agitate the said solids.

3. An entrainment device for forming a suspension of finely divided abrasive solids in a small stream of propelling gas for use in dental and surgical abrasive jet apparatus which comprises, in combination, a canister forming a reservoir for said solids, a wall structure defining an upright entrainment chamber laterally contiguous to said reservoir, said wall structure having a solids intake port interconnecting said entrainment chamber and a lower part of said canister, a gas inlet to said chamber adapted for connection to a source of said propelling gas under pressure and providing beneath said port and in proximity thereto a restricted flow passage small in relation to the cross-section of the entrainment chamber for directing said gas at high velocity with an upward velocity component in proximity to said port to

5 generate a low pressure within the chamber at said opening and to form an ascending suspension of said solids in the gas within the chamber, an outlet for discharging said suspension from the chamber adapted for connection to a conduit suitable for transporting said suspension, and a passageway connected to receive gas from said source and including a flow director for directing said gas into the canister into the solids therein for agitating the solids.

10 4. An entrainment device according to claim 3 wherein in said passageway interconnects a region of said entrainment chamber above the solids intake ports with the canister, wherein said gas directed into the solids contains suspended solids.

15 5. An entrainment device according to claim 3 wherein in said flow director is situated at an elevated part of the canister and is disposed to direct gas downwardly.

6. An entrainment device according to claim 3 wherein in said gas inlet to the entrainment chamber includes a capillary tube with a diameter of about 0.2 to 2 mm.

7. An entrainment device according to claim 3 wherein in said gas inlet to the entrainment chamber includes an orifice having therein an orifice with a diameter of about 0.2 to 2 mm.

20 8. An entrainment device according to claim 3 wherein in said wall structure provides a plurality of solids intake ports and said gas inlet provide a corresponding plurality of orifices, each orifice being situated in proximity to a solids intake port.

30 9. An entrainment device for forming a suspension of finely divided abrasive solids in a small stream of propelling gas for use in dental and surgical jet apparatus which comprises, in combination, a canister forming a reservoir for solids, an upright tube within said canister defining within itself an entrainment chamber, said tube having a plurality of solids intake ports near the bottom, a gas inlet to said tube at the bottom thereof adapted for connection to a source of said propelling gas under pressure and providing beneath said ports a restricted flow passage small in relation to the cross-section of the tube for directing said gas at high velocity upwards past said ports to generate a low pressure region within the tube and to form an ascending suspension of said solids in the gas within the tube, an outlet discharging said suspension from an elevated part of the tube adapted for connection to a conduit suitable for transporting said suspension, and a passageway interconnecting a part of the tube higher than the solids intake ports with the canister and including a flow director for directing a portion of said suspension into the solids in the canister for agitating the solids.

40 10. An entrainment device according to claim 9 wherein in said outlet includes a vertical outlet conduit situated within said tube in communication with said tube at said elevated part of the tube.

45 11. An entrainment device according to claim 9 wherein in said flow director is shaped to direct said suspension downwardly with a whirling motion.

50 12. An entrainment device according to claim 9 wherein in said outlet includes a vertical outlet conduit situated within said tube and having lateral intake ports establishing communication with said tube at said elevated part of the tube, and a deflector immediately above said lateral ports for deflecting solids into the ports, said deflector occupying only a portion of the cross-sectional area of the tube for the continued passage of a portion of the suspension upwardly beyond the deflector, said deflector being lower than the communication to said

55 passageway through which a portion of the suspension flows into the canister.

60 13. An entrainment device according to claim 12 wherein in said deflector is circumferentially discontinuous and said deflector and outlet conduit are relatively 65 rotatable, whereby the effectiveness of said deflector for

deflecting solids into the lateral intake ports can be adjusted.

14. An entrainment device for forming a suspension of finely divided abrasive solids in a small stream of propelling gas for use in dental and surgical abrasive jet apparatus which comprises, in combination, a canister defining an entrainment chamber communicating with the canister through a solids intake opening, a gas inlet to said chamber adapted for connection to a source of said propelling gas under pressure situated near said solids intake opening and providing a restricted passage small in relation to the cross-section of the entrainment chamber and opening into the entrainment chamber in advance of said solids intake opening so as to direct a jet of propelling gas at high velocity past the said opening and to generate a low pressure within the chamber

10

at said opening, an outlet for discharging said suspension from the chamber, and means for admitting gas into said canister.

5 15. An entrainment device according to claim 14 wherein said wall structure has a plurality of solids intake openings and said gas inlet to the chamber includes a separate restricted passage for each intake opening situated to form a separate jet of propelling gas opposite each of said intake openings.
